UNITED STATES PATENT OFFICE

FRED FEHR, OF PALISADE, NEW JERSEY

DESIGN FOR AN EMBROIDERED LACE EDGING

Application filed August 4, 1931. Serial No. 40,769. Term of patent 3½ years.

To all whom it may concern:

Be it known that I, FRED FEHR, a citizen of the United States of America, residing at Palisade, in the county of Bergen and State of New Jersey, have invented a new, original, and ornamental Design for Embroidered Lace Edging, of which the following is a specification, reference being had to the ac-

companying drawing, forming part thereof.

The figure is a plan view of the embroidered lace edging showing my design.

I claim:

The ornamental design for embroidered lace edging, as shown.

FRED FEHR.
